UNITED STATES PATENT OFFICE.

JERRY STANEK, OF HOMESTEAD, MONTANA.

TOY.

1,334,813.

Specification of Letters Patent. Patented Mar. 23, 1920.

Application filed October 21, 1919. Serial No. 332,185.

To all whom it may concern:

Be it known that I, JERRY STANEK, a citizen of the United States of America, residing at Homestead, in the county of Sheridan and State of Montana, have invented new and useful Improvements in Toys, of which the following is a specification.

The present invention has reference generally to improvements in that class of inventions known as games and toys and more particularly relates to an improved toy.

As the primary aim and object this invention contemplates the provision of coöperative means for supporting a flag in such a manner that the flag may be extended therefrom or else rolled up and inclosed therein.

More particularly, the present invention embraces the provision of novel coöperative supporting members one of which is rotatably receivable within the other and has connected thereto a flag which may be extended through the outer member or else upon the rotation of the inner member rolled upon said member and concealed within the outer member.

It is an additional object of this invention to provide a head on the inner rod which will rotate therewith when the flag is being actuated.

More particular objects of the present invention consist in the provision of coöperative bearing means on the respective ends of the rod for engagement with the respective ends of the supporting sleeve, so as to prevent relative longitudinal movement of the parts; to also provide the outer sleeve with means to permit of an easy engagement of the fingers of the user with the outer edge of the flag so that it may be extended when desired; and to also provide means for rotating the rod.

Among the other aims and objects of this invention may be recited the provision of a device of the character mentioned with a view to compactness, and in which the number of parts are few, the construction simple, the cost of production low and the efficiency high.

Other improvements and novel details in the construction and arrangement of parts of the apparatus will be brought out more in detail in the description to follow, which for a clear understanding of the invention should be considered in connection with the accompanying drawings, forming a part hereof, and wherein is disclosed for the pur-

pose of illustration a convenient and satisfactory embodiment of the invention.

The invention is clearly illustrated in the accompanying drawings, in which—

Figure 1 is a front elevation of the invention, the flag being arranged within the sleeve;

Fig. 2 is a vertical section taken through the sleeve, the flag being shown extended;

Fig. 3 is a fragmentary elevation of the sleeve;

Fig. 4 is a perspective view of the supporting rod;

Fig. 5 is a fragmentary front elevational detail of the supporting rod and the flag.

Similar reference characters are employed throughout the several views, to indicate corresponding parts.

Referring now, more particularly, to the accompanying drawings there is provided a supporting sleeve 1 which may be and preferably is formed of suitable metal while formed adjacent the upper end of the sleeve is a longitudinal slot 2 for a purpose that will presently appear. At opposite points substantially intermediate the end of the slot the sides thereof are provided with opposed finger receiving recesses 3 the particular purpose of which will presently appear.

Arranged throughout the sleeve is a supporting rod 4 which is provided adjacent its upper end with spaced annular grooves 5, the grooves being arranged preferably adjacent the respective ends of the slots 2 while connected in the grooves are the inner ends of a flag 6, the flag being preferably secured by means of pieces of cord 7 which are wrapped in the grooves about the ends of the flag as indicated in Fig. 5 of the drawings. As will be appreciated by the arrangement described the flag is designed to be extended through the slot and when the rod is rotated will be rolled about the rod so as to be consequently arranged within the sleeve. A head 8 is now provided and is desirably indicative of the head of Uncle Sam. A neck 9 issues from the head and has the inner end reduced while the outer edge of the reduced end is provided with an interiorly threaded socket 11 in which is removably engaged the upper threaded end 12 of the rod 4. When the head is in engagement with the rod it is designed that the shoulder formed when the end 10 is reduced be arranged in close rela-

tion to the neck 9.

tion with the upper edge of the sleeve while the reduced end itself is arranged in close relation with the inner wall of the sleeve 1 adjacent the upper end thereof. This reduced neck in effect provides a bearing which coöperates with a collar 13 carried adjacent the opposite end of the rod 4. The collar has one portion reduced as at 14 providing the shoulder 15 which shoulder is 10 arranged in close relation with the lower edge of the sleeve 1 while the reduced end 14 is arranged within the lower edge of the sleeve. Of course the neck and collar co-operate with each other in preventing undue longitudinal movement, at the same time being arranged in close relation with the inner walls of the sleeve forming bearings so as to facilitate an effective rotation of the rod. An eye 16 is formed on the 20 outer end of the rod and enables the user to rotate the rod so as to roll the flag 6 thereupon and draw it through the slot. The provision of the finger receiving recesses 3 of course permits of the user to 25 arrange his fingers in the recesses so as to engage the outer edge of the flag and draw it outwardly. During the rotation of the rod whether the flag is being wound or unwound owing to the substantially rigid relation between the rod and the head the head 30 will be rotated so as to afford amusement to children.

It is thought in view of the foregoing that a further detailed description of the operation of the invention is entirely unnecessary. Likewise it is believed that the advantages of the invention will be readily apparent.

As many changes could be made in the 40 above construction and many apparently widely different embodiments of this invention could be made without departing from the scope thereof, and it is intended that all matter contained in the above description or shown in the accompanying drawings shall be interpreted as illustrative and not in a limited sense. It is also

to be understood that the language used in the following claims is intended to cover all the generic and specific features of the 50 invention herein described and all statements of the scope of the invention, which, as a matter of language might be said to fall therebetween.

Having thus fully described this invention, what is claimed as new and desired to be secured by Letters-Patent, is:

1. A device of the character described including a supporting sleeve having a longitudinal slot therein adjacent one end, a supporting rod arranged in the sleeve, a flag arranged through the slot and connected to the rod, a head having a neck issuing therefrom for engagement with the rod, the neck of the head being reduced and arranged in 60 close relation with the upper edge of the sleeve and constituting a bearing, a reduced bearing collar carried by the opposite end of the rod and arranged in close relation with the lower edge of the sleeve and co-operating with the reduced neck of the head 65 for preventing longitudinal movement of the rod, and a finger loop formed on the outer end of the rod for facilitating the rotation of the rod and the head for winding 70 the flag upon the rod.

2. A device of the character described including a sleeve having a longitudinal slot adjacent the upper edge thereof, the sides of the slot being provided with opposed finger receiving recesses, a rod arranged within the sleeve, bearings carried by the respective ends of the rod for facilitating the rotation of the rod and for preventing longitudinal movement of the rod, a flag 85 arranged through the slot, means for connecting the inner end of the flag to the rod, and means formed on the outer end of the rod to facilitate the rotation thereof to consequently roll the flag upon the rod and 90 draw it within the sleeve.

In testimony whereof I affix my signature.

JERRY STANEK.
